UNITED STATES PATENT OFFICE.

JAMES T. ROBB, OF BAY SHORE, NEW YORK.

LIGHTING-FIXTURE FOR ATTACHMENT TO BEDROOM FURNITURE.

1,356,312.

Specification of Letters Patent. Patented Oct. 19, 1920.

Application filed December 19, 1919. Serial No. 346,060.

To all whom it may concern:

Be it known that I, JAMES T. ROBB, a subject of the King of Great Britain, residing at Bay Shore, in the county of 5 Suffolk and State of New York, have invented an Improvement in Lighting-Fixtures for Attachment to Bedroom Furniture, of which the following is a specification.

10 My invention relates to lighting fixtures of the character employed in sleeping apartments and attached to dressers, bedsteads or other articles of furniture. When installing fixtures of this kind it has usually been the practice to bore holes through the furniture for the passage of the conductor wires, and to attach the fixture to the face of the furniture over such bore. Furthermore, swinging fixtures are usually 15 employed, which are often roughly handled, especially in hotels by transient guests, causing injury to both the fixtures and furniture.

The object of my present invention is to 20 provide an attachment for such fixtures without defacement of the furniture, which may be readily attached or detached, and which holds the lamp in a fixed position, so that there will be no occasion for its adjustment by the occupant of the room, and when removed or placed in another position upon a piece of furniture, will leave no mark or disfigurement upon the face of the article to which it is attached. The details 25 of the invention are hereinafter particularly described.

In the accompanying drawing:

Figure 1 is an elevation of a dresser, illustrating the manner in which my invention 30 is attached thereto, the lamps and their supporting arms being removed for clearness.

Fig. 2 is a side view, partly in section, of one of the fixtures complete.

Fig. 3 is a front view of one of the bracket 35 members.

Fig. 4 is an end view of the same.

Fig. 5 is a front view of a bracket member suitable for attachment to the head board of a bedstead.

50 Fig. 6 is a broken vertical section of one of the bracket members showing a slight modification.

Fig. 7 is a similar view showing another modification, and

55 Fig. 8 is a similar view of another modification.

Similar reference characters denote like parts throughout the several views.

10, indicates the bracket members each having a straight vertical edge 11, on one side and a lateral flange 12, on the same side sunken below the surface of the straight edge so that it projects in line with the back surface of the bracket, otherwise these bracket members may be of any 15 desired configuration and ornamentation.

They are preferably made of metal, but may be made of wood corresponding to that of the furniture to which they are to be attached.

70 Each bracket member is provided with an opening 13, for the passage of conductor wires (not shown). These bracket members are usually employed in pairs (as illustrated in Fig. 1), formed for right and 75 left hand attachment to a piece of furniture; that is, the straight edge and flange on one bracket of a pair are formed on the opposite side to that of the other bracket of the same pair, except in cases 80 where the brackets are of such configuration and ornamentation that this is not necessary, such for instance, as shown in Fig. 5.

The flange 12, on each bracket is provided 85 with two or more screw-holes 14.

In Fig. 1 I have illustrated a pair of the brackets attached to a dresser 15. These are connected to the posts 16, supporting the mirror 17.

The straight edges 11, of the brackets 90 bear against the outer sides of the posts, while the flanges 12, bear against the rear surface of the posts to which they are secured by screws passing through the holes 14, in the flanges.

95 Fig. 2, for the passage of the conductor wires are thus brought clear of the posts, rendering it unnecessary to bore holes through the posts for that purpose, nor is the front surface of the posts marred 100 in any manner.

105 Fig. 3 is a front view of one of the bracket members. 18 denotes a tubular arm connected at one end with the bracket 10, by any suitable means, but in such manner that the opening therein registers with the opening 13, in the bracket. The opening in the free end of this arm is screw-threaded to receive the threaded end of the lamp socket 19, which holds the incandescent lamp 20. An ornamental shade 21 is preferably employed, 110 which is supported upon the socket in any suitable manner.

The arms 18, may be of any desired configuration and ornamentation, but are preferably of a predetermined length so as to support the lamps in the desired relative position to the article of furniture on which they are employed.

The end of the arm 18, connected with the bracket member 10, may be provided with a flange 22, and secured to the bracket by 10 screws 23, as shown in Fig. 2; or the opening 13, in the bracket member may be threaded, and the end of the arm exteriorly threaded to screw thereon as illustrated in Fig. 7. In cases where the bracket members are made of wood, it is preferable to provide a bushing 25, for the openings 13, having a threaded end extending forward of the face of the bracket upon which the end of the arm 18, may be screwed, as 15 shown in Fig. 8. The bushing may be provided with an annular flange 26, secured to the back of the bracket by screws 27.

By the employment of my invention, the objectionable feature of boring holes 20 through the furniture for the passage of

the conductor wires, heretofore experienced, is entirely avoided, and lighting fixtures may be attached to or removed from articles of furniture without the least defacement of the furniture, and there is less likelihood of 30 injury to the fixture itself, because of its fixed position.

I claim as my invention:

A device for supporting an incandescent lamp upon a dresser or other article of furniture, consisting of a substantially flat bracket member offset intermediate its width forming a straight edge adapted to bear against one side of the dresser post, the offset portion being provided with screw 35 holes for attachment to the article of furniture at its rear, the exposed portion of the bracket having an opening, a bushing within said opening secured to the bracket member, and a tubular arm connected to said bushing 40 in register with said opening.

Signed by me this 21st day of November 1919.

JAMES T. ROBB.
